UNITED STATES PATENT OFFICE.

LOUIS U. JOEDICKE, OF WEBSTER GROVES, MISSOURI.

MEANS FOR FORMING LINES OF STITCHES.

1,333,545.

Specification of Letters Patent. Patented Mar. 9, 1920.

Application filed November 27, 1917. Serial No. 204,187.

To all whom it may concern:

Be it known that I, LOUIS U. JOEDICKE, a citizen of the United States of America, a resident of Webster Groves, St. Louis county, State of Missouri, have invented certain new and useful Improvements in Means for Forming Lines of Stitches, of which the following is a full, clear, and exact description, reference being had to the accompanying drawings, forming a part of this specification.

This invention relates to improvements in means of forming lines of stitches, and more particularly to a means whereby continuous adjacent lines of lock stitches can be formed simultaneously. Prior to this invention, continuous adjacent lines of chain stitches have been formed by using a single machine having a plurality of needles, etc., for forming the chain stitches, the needles being close to each other so as to form the stitches in adjacent lines. However, it has been both difficult and expensive to form more than two rows of lock stitches in continuous adjacent lines. Each lock stitch forming device must include an individual shuttle and other elements associated therewith to form only one of the rows of lock stitches, and the elements of one lock stitch forming device must not interfere with the others. Owing to the fact that each individual shuttle, etc., occupies considerable space, for example, a space about 1 inch in width, the needles must be accordingly separated from each other to properly coöperate with the shuttles. In other words, the combined widths of several shuttles with their bobbins, etc., is so great that the ordinary lock stitch sewing machine cannot simultaneously form several rows of stitches in lines very close to each other.

Heretofore, a lock stitch sewing machine for stitching thick, heavy cloth or the like has been made with a single needle bar provided with a pair of needles separated from each other a distance of about 1 inch, and lines of lock stitches 1 inch apart having been satisfactorily formed by said machine. To accomplish this, the individual shuttles, etc., of the earlier machine have been arranged very close to each other, leaving no unnecessary space between them, and as a consequence, a third individual shuttle etc. could not be interposed for the purpose of forming a third line of stitches between the two lines just referred to. In actual practice it is frequently necessary to form three

continuous lines of lock stitches in a space about 1 inch wide, and, prior to the present invention, two separate and distinct operations have been performed in making the three adjacent lines of stitches. The work has been fed and guided through a machine having two needles about 1 inch apart, so as to form two of the lines of stitches, and upon the completion of this operation the stitched work is taken away from the double needle machine, the third row of stitches being subsequently formed by feeding and carefully guiding the work through another lock stitch machine. This is the ordinary method of forming more than two adjacent lines of lock stitches in heavy sheets of canvas as large as thirty feet square, the work being pulled over the floor of the work room and at the same time carefully guided and otherwise manipulated during each of the two separate and distinct operations. In performing the second operation, considerable time and labor is required and great care must be exercised in guiding the work to accurately form the third line of stitches between the two adjacent lines of stitches.

By using the new machine the several continuous adjacent lines of lock stitches are formed simultaneously, and actual experience has shown that the work can be done in about one-fifth of the time required to do the same work in the old way. Three or more continuous lines of lock stitches can be readily formed in a space about 1 inch wide, and the work can be easily guided so as to accurately form the stitches in straight parallel lines. Many large, heavy bodies of cloth have been stitched by the new machine, and I have found that work formerly requiring two and one-half hours time can be completed in one-half of an hour. The adjacent lines of lock stitches are formed more accurately, and the care and labor heretofore involved in the second stitching operation is entirely eliminated.

Briefly stated, the preferred form of the invention includes means for simultaneously forming more than two adjacent rows of lock stitches at separated lock stitch forming devices, and at the same time continuously advancing the work from one of said stitch forming devices to the other. A portion of the work is interposed between the separated lock stitch forming devices, and the work is preferably fed by pushing said interposed portion away from one of the stitch forming

devices and at the same time pulling it toward the other stitch forming device. To accurately form the stitches in adjacent parallel rows, the interposed portion of the work can be easily guided in a straight line from one of the stitch forming devices to the other.

With the foregoing and other objects in view the invention comprises the novel construction, combination and arrangement of parts hereinafter more specifically described and illustrated in the accompanying drawings wherein is shown the preferred embodiment of the invention; however, it is to be understood that the invention comprehends changes, variations and modifications which come within the scope of the claims hereunto appended.

Figure I is a plan view of an apparatus embodying the features of my invention.

Fig. II is a side elevation of the structure shown in Fig. I.

Fig. III is a side elevation, partly in section, showing the side opposite to that illustrated in Fig. II.

Fig. IV is a front elevation of the apparatus.

Fig. V is a diagrammatical plan view of the separated lock stitch forming devices, showing the needles, shuttles and bobbins.

Fig. VI is a fragmentary detail view showing a portion of the means for transmitting movement to the shuttles.

Fig. VII is a detail view showing a portion of the means for feeding the work.

I do not deem it necessary to show or describe all of the minor details of construction usually employed in lock stitch sewing machines, for the invention is not in any way limited to such minor details, and any suitable lock stitch forming devices could be used to obtain the advantages herein pointed out. The drawings are therefore more or less diagrammatical illustrations of the mechanism, and I will endeavor to set forth the invention without describing many details which are well known to those skilled in the art.

The structure herein shown comprises two complete lock stitch sewing machines, designated A and B, respectively, separated from each other as shown in Figs. I and IV, the work being advanced from the machine A to the machine B, as indicated by arrows in Figs. I, IV and V. The machine A is provided with a pair of needles 1 secured to a horizontal foot 2 at the lower end of a vertical needle bar 3, but the machine B is provided with only one needle 1' secured to a needle bar 3'. An oscillatory shuttle 4' provided with a bobbin 5', is mounted below the single needle 1' (Figs. IV and V) to coöperate therewith in a manner well understood in this art. The shuttle 4' is loosely mounted in a stationary circular member 6' (Fig.

IV). 7' designates an oscillatory shuttle driver fixed to a shaft 8' and provided with a flange 9' adapted to strike the shuttle 4' (Fig. IV). The shaft 8' is oscillated, as will be hereinafter described, for the purpose of oscillating the shuttle driver 7', thereby transmitting the oscillatory movement to the shuttle 4'.

The machine A, having a pair of needles 1, is also provided with two individual shuttles 4 (Figs. IV and V) each having a bobbin 5 and an oscillatory shuttle driver 7 fixed to a shaft 8. It will now be understood that each of the machines A and B is provided with an individual shuttle operating shaft 8 or 8', and that the machine A has two needles which coöperate with a pair of shuttles, while the machine B has only one needle and only one shuttle.

The needles and shuttles are separated from each other in such a manner that three straight parallel lines of lock stitches can be formed simultaneously by feeding the work W from the pair of needles 1 to the single needle 1', as indicated by arrows in Figs. I, IV and V. The stitches 1^a (Fig. I) are formed by the pair of needles 1 and the shuttles associated therewith, while the single line of stitches 1^b (Fig. I) is formed by the machine B having only one needle. It will be observed that the line of stitches 1^b is formed between the lines of stitches 1^a, and that these adjacent lines of stitches can be formed very close to each other, although the shuttle mechanism of one of the stitch forming devices is widely separated from the shuttle mechanism of the other device. By referring to Fig. V it will be noted that the single shuttle 4' and its bobbin 5' could not be interposed between the corresponding parts of the machine A, and for this reason the machine A could not be modified to receive a third shuttle and bobbin between its pair of shuttles. The elements of the machine A are so constructed that there is no unnecessary space between the pair of shuttles, and in actual practice I have found that the pair of needles 1 can be conveniently arranged about 1 inch apart, although it is to be understood that the invention is not limited to any particular dimensions, the object being to obtain all of the advantages herein referred to by simultaneously forming the adjacent lines of lock stitches.

The work is lapped and folded, as suggested by Figs. I and III, to receive the stitches 1^a and 1^b, and one of the lapped edges of the work engages the edge 10' of a straight guide bar 10, shown in Figs. III and V. This guide bar is arranged on the work receiving table and it extends approximately from one stitch forming device to the other. The work can be easily guided across the work table, in a straight line, by maintaining one of the lapped edges in en-

gagement with the straight edge 10' of the guide bar 10. Therefore, the three adjacent rows of stitches can be readily formed in parallel lines.

5 Each of the machines herein shown comprises a main shaft 12, provided at its front end with a head 13 (Figs. II and IV) and a connecting rod 14 whereby said head is connected to the needle bar 3 or 3'. The respective ends of each connecting rod 14 are pivotally connected to the head 13 and needle bar 3 or 3'. Each needle bar is guided so as to move vertically in response to the rotary movements of the main 15 shaft 12.

The means for actuating the shuttles includes the oscillatory shafts 8 and 8' (Figs. II, III, IV and VI) to which the respective shuttle drivers 7 and 7' are secured, and 20 each of the shafts 8—8' is provided with an arm 15 (Figs. III and VI) having a pin 16 on which a block 17 is pivotally mounted, said block being arranged in the slotted arm 18 of a bell crank lever 19. This bell crank 25 lever is pivoted at 20 and connected, by means of a long connecting rod 21, to a crank 22 formed in the rotary main shaft 12 (Figs. IV and VI). In response to the rotary movement of the main shaft 12, the 30 long connecting rod 21 is actuated so as to oscillate the bell crank lever 19 (Figs. III and VI) thereby transmitting an oscillatory movement to the arm 15 and shuttle actuating shaft 8 or 8'. It is to be understood 35 that each machine A and B is provided with the mechanism just described, for the purpose of oscillating its shuttle actuating shaft 8 or 8'.

Each of the machines is also equipped 40 with a take-up device in the form of an L-shaped lever 23 (Figs. I, II and III), pivoted at 24 and having a pin or roller 25 which extends into a cam groove 26 formed in the head 13 at the front end of the main 45 shaft 12.

Each presser foot 27 is secured to the lower end of a bar 28, the upper end of said bar being pivoted at 29 to a hook 30 (Figs. II and III) secured to a vertically 50 movable rod 31. A long leaf spring 32, engaging the upper end of rod 31, forces the latter downwardly, and since the hook 30 (Figs. II and III) is secured to said rod 31, the bar 28 and its presser foot 27 are also 55 forced downwardly by the spring 32. The presser foot can be lifted manually through the medium of a lever 33, pivoted at 34 (Fig. IV) and also pivotally connected, at 35, to a link 36, the lower end of said link being 60 slotted as shown in Fig. IV, to receive the pivot pin 29 whereby the bar 28 is secured to the hook 30.

When the machine is in operation, each 65 presser foot is intermittently lifted, lowered and oscillated for the purpose of feeding the

work. To raise and lower its presser foot, each machine is provided with a bell crank lever 37 (Fig. III) pivotally supported at 38 and pivoted at 39 to the vertically movable rod 31, the latter being connected to the 70 presser foot as previously pointed out. Each bell crank lever 37 (Fig. III) has an adjustable extension 37' provided with a roller 40 engaging a cam 41 on the head 13 at the front end of the main shaft 12. Motion is 75 transmitted from the main shaft, through the cam 41 and bell crank lever 37, for the purpose of lifting the presser foot, and the long leaf spring 32 is utilized to lower the 80 presser foot. The means for oscillating the 85 presser foot, to feed the work, comprises a horizontal shaft 42 (Figs. II, III and IV), an arm 43 depending from said shaft, and a roller 44 projecting laterally from the lower end of said arm 43 and extending into the 90 lower portion of the bar 28 to which the presser foot is secured. The shaft 42 is oscillated so as to oscillate the bar 28 and its presser foot 27, about the axis of the pivot pin 29 at the upper end of said bar 28. The 95 means for oscillating said shaft 42 comprises an arm 45 extending from said shaft, a link 46 connecting said arm 45 to an arm 47 on a shaft 48 (Figs. III, IV and VII) the last mentioned shaft being provided 100 with an arm 49 actuated by a cam 50 on the main shaft 12. The arm 49 and cam 50 are shown most clearly in Figs. III and VII. Motion is transmitted from the main shaft 12 and through the mechanism just described so as to oscillate the presser foot, and each machine is provided with mechanism of this kind. If desired, the usual feed dogs 51 (Fig. V) can be located adjacent to the needles so as to coöperate with the 105 presser feet, in a manner well understood in the art.

The thread T passing to the single needle of the machine B (Figs. I, III and IV) is drawn from any suitable source of supply, 110 and it passes through a tension device 52 near the upper portion of the machine (Fig. III), thence downwardly to a tension device 53, upwardly to take-up lever 23 and downwardly (Fig. IV) to the needle 1'. The 115 machine A is provided with devices similar to those just described, for the purpose of tensioning and guiding the two threads passing to the pair of needles 1.

A belt 54 may be utilized to transmit 120 power to a pulley 55 on the main shaft 12 of the machine A. To properly operate the machines A and B they should be driven from a common source of power, and each main shaft 12 is therefore provided with 125 a sprocket wheel 56 fitted to a sprocket chain 57 whereby motion is transmitted from the main shaft 12 of the machine A to the corresponding shaft of the machine B. I do not deem it necessary to point out the de- 130

tails of the several operations necessary to form the lock stitches, nor the manner in which the successive operations are performed, however, it will be noted that the 5 elements of the machine B are arranged slightly in advance of the corresponding elements of machine A. This is shown most clearly in Fig. IV, particular attention being directed to the positions of the shuttle 10 and needle mechanism of the different machines. The sprocket wheels 56 are adjustably secured to the main shafts by means of set screws 58, and by loosening and properly adjusting these sprocket wheels, the elements of one machine can be easily positioned in advance of the corresponding elements of the other machine. I will now set forth the reasons for adjusting the machines in this manner.

20 When the machines are in operation, a portion of the work is interposed between the separated lock stitch forming devices, and the presser feet coöperate with each other to feed the work. The work is pushed 25 forwardly by the presser foot of the machine A and pulled in the same direction by the presser foot of the machine B. By arranging the elements of machine B in advance of the elements of machine A, the 30 feeding operation is performed in approximately the following manner. The portion of the work interposed between the lock stitch forming devices is first pulled by the feeding elements of machine B and thereby 35 placed under tension. Immediately thereafter, the feeding elements of machine A are actuated and the tensioned portion of the work is then advanced by the feeding elements of both machines. At this time the 40 interposed portion of the work is pulled forwardly by the machine B and pushed in the same direction by the machine A. Upon the completion of the feeding operation performed by machine B, the tension of the 45 work is relieved by the machine A which continues to push the work a slight distance. By feeding the work in this manner I overcome the tendency of the work to buckle or become somewhat loose between 50 the two lock stitch forming devices.

It will now be understood that the elements of the structure herein disclosed are combined with each other so as to coöperate in forming continuous adjacent lines of 55 lock stitches, and that this is accomplished by simultaneously forming more than two continuous lines of lock stitches at separated lock stitch forming devices, and at the same time continually advancing and guiding 60 the work from one of said lock stitch forming devices to the other. The single row of lock stitches formed by the machine B, is interposed between the two rows of stitches formed by the other machine, and 65 this interposed row may be formed in a line

midway between the other two rows, or in a line relatively close to one of the last mentioned rows. The position of the interposed line is determined by the position of the machine B relative to the machine A, and 70 said machine B can be adjusted longitudinally.

With this end in view, the machine B may be provided with legs 59 (Fig. III) mounted on supports 60 and adjustably secured thereto by means of screws 61 passing through slots 62 in the legs 59. The sprocket wheels 56, adjustably secured to the main shafts by means of set screws 58, can also be adjusted when the machine B is adjusted 80 longitudinally relative to the machine A.

The apparatus herein shown is particularly adapted for use in handling very large bodies of thick heavy canvas, or the like, and it has been found quite difficult to manipulate such material at the points where it is admitted to the machine. To overcome friction at these points and to enable the operator to more easily handle the material, a long horizontal anti-friction roller 63 85 (Figs. I, II and IV) is rotatably mounted near the machine A, and a similar roller 64 is mounted near the machine A, and a similar roller 64 is mounted in a vertical position at a point near the roller 63. The horizontal roller is located near one edge of the work receiving table to engage the bottom face of the work passing to the machine A. A large portion of the work is arranged in irregular folds and crowded between the vertical roller and the stitch forming devices. 90 95 100

I claim:

1. In a mechanism for simultaneously forming more than two lines of lock stitches, a succession of lock stitch forming devices 105 separated from each other, one of said lock stitch forming devices being provided with a pulling device whereby the work is pulled from the other lock stitch forming device, and the last mentioned stitch forming device being provided with a pushing device coöperating with said pulling device to advance the work, said pulling device being arranged in advance of the pushing device and adjusted to pull and tension the work 110 before the latter is pushed by said pushing device, and operating means common to all of said devices.

2. In a mechanism for simultaneously forming more than two lines of lock stitches, 120 a succession of lock stitch forming devices separated from each other, each of said lock stitch forming devices including a shuttle, the shuttle of one device being arranged in advance of the shuttle of the other device, and feeding devices coöperating with each other to advance the work from one of said lock stitch forming devices to the other, one of said lock stitch forming devices being adjustable transversely of the path of the work 125 130

so as to provide for the formation of the rows of stitches in different lines relative to the stitching formed by the other stitch forming device.

5 3. In a mechanism for simultaneously forming three lines of lock stitches, a succession of lock stitch forming devices separated from each other, one of said devices being provided with a needle and a shuttle
10 and the other being provided with two needles and two shuttles, the first mentioned needle being arranged in a line between said two needles to provide for the formation of a line of stitches between the lines of stitches
15 formed by the two needles, and said succession of stitch forming devices being provided with feeding elements whereby the work is advanced from one of said stitch forming devices to the other, one of said lock
20 stitch forming devices being adjustable transversely of the path of the work so as to provide for the formation of the rows of stitches in different lines relative to the

stitching formed by the other stitch forming device.

25 4. In a mechanism for simultaneously forming more than two lines of lock stitches, a succession of lock stitch forming devices separated from each other, each of said lock stitch forming devices including a shuttle, 30 the shuttle of one device being arranged in advance of the shuttle of the other device, feeding devices coöperating with each other to simultaneously push and pull the work from one of said lock stitch forming devices 35 to the other, and operating means common to all of said devices, said operating means including a power transmission member adjustable to locate the movable elements of one lock stitch forming device in advance 40 of the corresponding elements of the other lock stitch forming device.

In testimony that I claim the foregoing I hereunto affix my signature.

LOUIS U. JOEDICKE.
